CLAIM

The ornamental design for a frame molding for panel
structures, as shown and described.

DESCRIPTION

FIG. 1 is a perspective view of a frame molding for
panel structures, showing my new design;

FIG. 2 is a top-plan view thereof;

FIG. 3 is a bottom-plan view thereof;

FIG. 4 is a front-elevational view thereof;

FIG. 5 is a rear-elevational view thereof;

FIG. 6 is an enlarged cross-sectional view taken along
line 6—6 of FIG. 4;

FIG. 7 is a perspective view of a frame molding for
panel structures showing a second embodiment of my
new design;

FIG. 8 is a top-plan view thereof;

FIG. 9 is a bottom-plan view thereof;

FIG. 10 is a front-elevational view thereof; and

FIG. 11 is a rear-elevational view thereof; and

FIG. 12 is an enlarged cross-sectional view taken along
line 12—12 of FIG. 10.
